J. H. WILHELM

EYES FOR TOY FIGURES

Filed March 27, 1926

Inventor
John H. Wilhelm

By his Attorney
H. Surfor Stand

UNITED STATES PATENT OFFICE.

JOHN H. WILHELM, OF LONG ISLAND, NEW YORK, ASSIGNOR TO MARKON MANUFACTURING CO. INC., OF NEW YORK, N. Y., A CORPORATION OF NEW YORK.

EYES FOR TOY FIGURES.

Application filed March 27, 1926. Serial No. 97,881.

This invention relates to eyes for toy figures, and particularly to eyes which are adapted to be manually moved to "open" and "closed" position.

5 An object of the present invention is to provide an eye set which may be readily mounted in operative position within a toy figure, such as a doll or animal head, and which when in position will provide a part 10 projecting exteriorly of the figure by which the eyes may be moved at will.

A further object is to provide a tongue member and to so connect it with the eyes that it will be moved into and out of the 15 mouth of the figure co-incident with the movements of the eyes.

A further object is to so construct the device that the operation thereof will be gravity controlled and so that the gravity movement of the parts is opposed to the manual control.

Other objects and aims of the invention, more or less specific than those referred to above, will be in part obvious and in part 25 pointed out in the course of the following description of the elements, combinations, arrangements of parts and applications of principles constituting the invention; and the scope of protection contemplated will 30 be indicated in the appended claims.

In the accompanying drawings which are to be taken as a part of this specification, and in which I have shown merely a preferred form of embodiment of the invention:—

Fig. 1 is a rear elevational view of an eye set constructed in accordance with this invention, and

Fig. 2 is a side elevational view of the 40 structure shown in Fig. 1 and illustrating the same in association with portions of a toy figure, in this instance being an animal head, and the movable parts being shown by dotted lines in abnormal position.

45 Referring to the drawings for describing in detail the structure therein shown the reference characters L and G indicate the two eyes of the set. These are connected together by the usual cross rod 1 to the opposite ends of which they may be connected 50 in any approved manner.

The cross rod 1 is mounted to oscillate

in a suitable bracket member H which extends into connection with a convenient wall portion of the toy figure where it is held in 55 any appropriate manner as by means of the cement 2 illustrated.

Fixed to the central portion of the cross rod 1 is a pendant rod 3 at the lower end of which is a weight 4 which is adapted to move by gravity for oscillating the rod 2 back and forth whenever the toy figure is moved from an upright to a reclining position, or vice versa.

Also fixed to the cross rod 1, and preferably comprising an extension of the rod 3, is a crank-arm 5 which projects a short distance from the rod 1 and is pivotally connected, as at 6, to the lower end of a link 7 which extends upwardly and is in turn 70 pivotally connected by its upper end, as at 8, with a manual control plunger 9, the latter continuing upwardly and slidably extending through an opening 10 provided as a guide bearing therefor in an upper wall 75 portion as 11 of the toy figure. The upper outer end of the plunger 9 is formed with a suitable "push button" portion 12 by which it may be manually depressed for oscillating the cross rod 1 in opposition to the gravity pull of weight 4 whenever desired to move the eyes from their normal "open" to their "closed" position.

Mounted to rotate freely upon the cross rod 1 is a U-shaped lever member 13, being 85 connected with rod 1 by having bearings as 14—14 at the upper ends of its two legs through which the rod 1 loosely extends, and said two legs being preferably arranged to straddle the bracket member H. 90 To the lower end of the lever is pivotally connected a tongue member 15 which extends loosely through an appropriate mouth opening 16 provided to slidably receive it in the toy figure.

95 The pivot connection between the lever 13 and the tongue 15 in the instance illustrated is effected by bending over the inner end portion of the tongue to provide a bearing opening as 17 through which the connecting portion as 18 of the U-shaped lever loosely extends.

100 At the upper end of one leg of the lever 13 is provided an extension or crank-arm

19 to the outer end of which, as at 20, is pivotally connected the lower end of the plunger 9.

By this means the tongue 15 will be projected outwardly through the mouth 16 whenever the plunger is depressed to swing the weight and actuate the eyes.

The bracket member H is shown as provided with a slot 21 within which the weight 10 carrying rod 3 moves, and it will be noted that the presence of the rod within this slot will serve to at all times hold the cross rod 1 against undue longitudinal movement within the bearing portions 22-22 of the 15 bracket, and that since the legs of the lever 13 straddle the bracket so as to engage the cross rod 1 closely adjacent opposite sides of the bracket said bracket is also held against undue longitudinal movement along 20 the cross rod 1.

While the plunger 9 and its push button 12, are shown projecting through a top wall portion of the figure head it will be readily appreciated that these parts may be located 25 in any other desired position, as for instance at a rear wall portion of the head, if desired, it being manifestly only necessary in such case to arrange the pivots 6 and 21 in a relatively rotated position so that they 30 would bear the same relation to the new position of the push button as they do in the instance illustrated.

If a doll, or animal, head having this invention comprised therein, be held in its 35 normal upright position, as shown by the full lines in Fig. 2, the weight 4 will be in its lowermost position holding the eyes "open" and, acting through the link 7 and plunger rod, holding the tongue 15 in its 40 inner position.

If now the push button 12 is depressed the weight will be swung backwardly to its dotted line, or eye closing, position and the lever 13 will be swung forwardly to project the tongue 15 as indicated by the heavy dotted lines.

As soon as pressure is relieved from the push button the gravity effort of the weight will restore the parts again to their normal 50 position.

If at any time the toy figure is moved from its upright to a reclining position the weight will move by gravity and produce the same result as if the button 12 had been 55 manually depressed, and here it may be noted that the eyes and tongue may be as readily actuated when the toy figure is in a reclining position as in its upright position, the button 12 requiring in this instance 60 only to be drawn outwardly from the guide opening 10, which movement will be opposed by the gravity movement of the weight which will in that case be tending to hold the eyes closed and the tongue projected.

As many changes could be made in this

construction without departing from the scope of the invention, as defined in the following claims, it is intended that all matter contained in the above description or shown in the accompanying drawings, shall 70 be interpreted as illustrative only and not in a limiting sense.

Having thus described my invention, what I claim as new and desire to secure by Letters Patent is:-

1. An eye set comprising a pair of eyes, a cross rod extending between and being connected with said eyes, a pivot bearing for said cross rod, means by which to oscillate said rod within said pivot bearing, a movable tongue, an operating member for said tongue, said operating member being pivotally mounted upon said cross rod by having bearing openings therethrough through which the cross rod loosely extends, and connections by which said operating member is arranged to be actuated by the means which serve to oscillate the cross rod.

2. An eye set comprising a pair of eyes, a cross rod extending between and being connected with said eyes, a pivot bearing for said cross rod, means by which to oscillate said rod within said pivot bearing, a movable tongue, an operating member for said tongue, said operating member being pivotally mounted upon and relative to said cross rod, and connections by which the means which serves to oscillate the cross rod is adapted also to actuate said operating member for moving said tongue.

3. An eye set for toy figures, said eye set comprising a pair of eyes, a cross rod extending between and connecting said eyes, a pivot bearing within which the cross rod is arranged to oscillate, an arm extending laterally of the cross rod fixed thereto carrying a weight at its outer end adapted to oscillate the cross rod, a second arm extending laterally of the cross rod fixed thereto, a manually operable push button adapted to be arranged exteriorly of the toy, figure connected with said second arm by which to manually move the cross rod, a movable tongue, and connections between the push button and the tongue to move the tongue by said push button simultaneously with oscillation of the cross rod.

4. An eye set for toy figures, said eye set comprising a pair of eyes, a cross rod extending between and connecting said eyes, a pivot bearing within which the cross rod is arranged to oscillate, an arm extending laterally of the cross rod fixed thereto carrying a weight at its outer end adapted to oscillate the cross rod, a second arm extending laterally of the cross rod fixed thereto, a manually operable push button adapted to be arranged exteriorly of the toy figure connected with said second arm by which to manually move the cross rod, a movable tongue, and a

bell-crank lever pivotally mounted upon the cross rod having one arm pivotally connected with the push button and the other with the tongue whereby to move the tongue by said 5 push button simultaneously with oscillation of the cross rod.

5. The combination with a hollow toy figure having eye openings, a mouth opening, and a further opening through the wall 10 thereof, of a pair of eyes arranged adjacent the eye openings respectively, means by which said eyes are oscillatably supported, a weight, connections between the eyes and the weight adapted to oscillate the eyes, a tongue 15 movable through the mouth opening, a rod slidable through said mentioned further opening guided at one end by contact of the walls of said opening, connections between said rod and said tongue to guide the other 20 end of said rod and move said tongue in response to movements of said rod, and sepa-

rate connections between said rod and said eyes to move said eyes by movement of said rod.

6. An eye set for toy figures, said eye set 25 comprising a pair of eyes, a cross rod extending between and connecting said eyes, a pivot bearing within which the cross rod is arranged to oscillate, a movable tongue, a pair of arms extending in opposite directions laterally from the cross rod one being thereby connected with the eyes and the other being pivotally mounted upon the cross rod, connections between the latter arm and the tongue, and a manually operable push button 30 device adapted to extend exteriorly of the toy figure having parts connected with said arms respectively to move said arms simultaneously by movement of the push button device.

In testimony whereof I affix my signature.
JOHN H. WILHELM.
